UNITED STATES PATENT OFFICE.

CHARLES STAHLBERG, OF NEW YORK, N. Y., ASSIGNOR TO THE ACCURATE TIME STAMP COMPANY, OF WEST VIRGINIA.

TIME-STAMP.

SPECIFICATION forming part of Letters Patent No. 591,021, dated October 5, 1897.

Application filed September 25, 1891. Serial No. 406,819. (No model.)

To all whom it may concern:

Be it known that I, CHARLES STAHLBERG, a resident of New York city, county, and State, have invented certain new and useful 5 Improvements in Time-Stampers, of which the following is a full, clear, and exact description, reference being had to the accompanying drawings and to the letters and figures of reference marked thereon.

10 This invention relates to and has for its object to provide an improved stamp in which the printing mechanism and motor therefor shall be contained in a single frame adapted to be inclosed in a relatively small casing.

15 The device is primarily intended to automatically present at the printing-point the indices for registering a proper month, day, hour, and minute, although certain features of the mechanism are well adapted for use in 20 connection with calendar devices in which the month, day, hour, &c., are adapted to be presented to view, as will be readily understood by those skilled in this art.

The invention consists in certain novel details of construction and combination and arrangement of parts, as will be hereinafter described, and pointed out particularly in the appended claims.

Referring to the accompanying drawings, 30 Figure 1 is a front elevation of a time-stamp and casing constructed in accordance with my present invention. Fig. 2 is a side elevation of the same. Fig. 3 is a top plan view of the operating mechanism and its frame. Fig. 4 is a rear elevation of the same. Figs. 35 5 and 6 are front elevations with portions broken away to show the train connections. Fig. 7 is a detail of the minute-wheel and its locking-lever with the releasing-cams there- 40 for in dotted lines. Fig. 8 is a detail of the date units-wheel, its locking-lever, and gearing immediately connected therewith. Fig. 9 is a similar view of the date tens wheel, showing the skipping-lever for the units- 45 wheel in full lines. Fig. 10 is a similar view of the month-wheel. Fig. 11 is a vertical section through the entire set of type-wheels. Figs. 12, 13, 14, and 15 are elevations of the month and hour, minute-tens, and minute- 50 units wheels, respectively. Fig. 16 is a cross-section of one of the type-wheels. Fig. 17 is

a detail perspective of the skipping mechanism. Figs. 18 and 19 are details of the same. Fig. 20 is a detail elevation of the releasing-cams for the date tens-wheel locking-lever. 55 Figs. 21 and 22 are details of the setting mechanism for the minute units-wheel. Fig. 23 is an elevation showing the relative location of releasing-cams for the month and date units and tens wheels, respectively. Fig. 24 60 is a detail section of one of the spring-drums. Fig. 25 is a projection of the date, hour, and minute wheels, showing the arrangement of the series of numerals thereon.

Similar letters and figures of reference in 65 the several figures indicate the same parts.

Difficulty has heretofore been experienced in this class of devices when it has been attempted to combine the type-wheel-operating mechanism and a spring-weight or other motor in the same case, due, primarily, to the extreme variation in the load carried by the spring, owing to the irregular action of the type-wheels, this being particularly the case 70 in connection with the minute and hour 75 wheels, which of necessity move quite frequently and must therefore be connected with a rapidly-moving, and consequently less powerful portion of the train, and it is with the object of overcoming this difficulty, as 80 well as to provide a more compact and easily-operated device, that I have designed my present invention.

In the following description I will first describe and point out the motor, or what I 85 shall herein term the "clock-train," which is somewhat peculiarly arranged, although not constituting an essential part of the invention so far as the successful operation of the type-wheel is concerned.

Referring now particularly to Figs. 3, 4, 5, and 6, it will be seen that two mainsprings or drums A are employed, located at the lower corners of the frame, which springs carry gear-drums 1, both of which mesh with a 95 gear-wheel 2, Fig. 5, mounted on a shaft 2^d, which communicates its motion to a gear-wheel 3, meshing with a pinion 4 on a shaft 4^d, and communicates its motion to a gear 5, meshing with a pinion 6 on a shaft 6^d, which 100 communicates the motion to a gear-wheel 7, meshing with a pinion 8 on a shaft 8^d, carry-

ing a gear-wheel 9, meshing with a pinion 10 on a shaft 10^d, which extends away through the frame to the rear side, as shown in Fig. 3, and carries a pair of gear-wheels 11 11^a, 5 Fig. 21, the former of which meshes with a pinion 12, mounted on a shaft 12^d, and carrying a gear-wheel 13, meshing with a pinion on the escapement-wheel shaft 14. (Shown in dotted lines, Fig. 4.) Immediately below 10 this shaft 14 is located a bearing for the pallet 15, the extended end of which coöperates with a pin 16, carried by the usual balance-wheel and hairspring arrangement 17. By thus locating the bearings for the escapement 15 and pallet shocks or vibrations imparted to the frame in a vertical direction, such as are caused by stamping upon the type-wheels, do not tend to vary the speed of the clock-train, as will be hereinafter more particularly mentioned. 20

Returning now to Figs. 3 and 5, it will be seen that the type-wheels are located, preferably, at about the center of the frame, near the top, on a single shaft B, in position to 25 bring any of their indices in line at the top, and the first three wheels and the hour and minute units and tens wheels are adapted to be driven from the clock-train by three systems of gearing, which may form branches 30 from the clock-train, in each of which branches is interposed what I shall herein term an "equalizing-spring"—that is to say, a spring which permits of the intermitting action of the type-wheels while the clock-train moves 35 regularly and at the same time prevents any variation of the load on the clock-train by reason of such intermitting action of the type-wheels.

The branch for driving the minute units-wheel, which is allowed to move once a minute by an escapement to be presently described, is as follows: Referring to Figs. 5 and 6, 2^a indicates a gear-wheel on the minute units-wheel and 1^a indicates a gear-wheel 40 meshing therewith journaled loosely on the shaft 8^d, but connected therewith through the medium of a small coil-spring 8^a. Thus when the shaft 8^d is rotated by the clock-train 45 before mentioned, it, through the medium of the spring 8^a, tends to rotate the minute units-wheel; but if said wheel is restrained then the power to move the same is stored in the spring 8^a, and in order to cause the proper movement of the minutes-wheel, as before 50 mentioned, a small pinion 3^a, journaled in the frame, meshes with the wheel 1^a and is mounted rigidly on a shaft 4^a, passing through to the back of the frame and carrying a stop-wheel 5^a, provided with a series of stop-points 55 which strike against a stop 6^a in the form of a shaft, which shaft has a small notch or cut-out portion thereon through which the points can pass when the shaft is properly rotated. This shaft is driven from the clock-train by 60 means of a pinion 7^a, which meshes with the wheel 11^a, before mentioned.

The pair of wheels 11 and 11^a, before men-

tioned, while they are mounted on the same shaft are yet capable of an independent rotation, which enables the wheel 11^a to be turned 70 and the minute units-wheel controlled thereby properly set. To accomplish this, the wheel 11, Fig. 21, is loosely journaled on the shaft 10^d, before mentioned, and is pressed against inclined face projections 9^a, Fig. 22, on said 75 wheel 11^a by means of the spring n, as shown in Fig. 21, which projection coöperates with suitable depressions or openings in the first-mentioned wheel and forms a clutch connection, thus under normal circumstances causing 80 the same to move in unison; but when the wheel 10^a, which meshes with the wheel 11^a, is turned by means of the knurl 11^c, Figs. 3 and 4, the type units-wheel will be turned in unison, while the running of the clock-train will not be interfered with unless it be 85 a slight acceleration of the escapement end of the train during the time the said operation is taking place. The gear 11^a, it will be seen, is directly in the type-wheel train. 90

The mechanism for driving the minute tens-wheel consists of a gear-wheel 2^b, mounted on said minute tens-wheel and meshing with a small gear 1^b, journaled loosely on the shaft 4^d, but connected therewith through a 95 coil-spring 4^b, similar to the one heretofore described.

The hour-wheel branch from the motor or clock-train commences with a gear-wheel 1^c, Fig. 5, mounted on the shaft 2^d, deriving its 100 motion therefrom and meshing with a wheel 2^e on a shaft 5^e, carrying a wheel 3^e, journaled thereon through the medium of a collar 20^e, Fig. 24, and connected to said wheel through the medium of a spring 4^e and drum 21^e, similar 105 to the spring 8^a. The wheel 3^e meshes with a gear-wheel 6^e, carried by the hour-wheel.

In Fig. 11 the year-wheel is indicated by the letter B', the minute units-wheel B², minute tens-wheel B³, hour-wheel B⁴, date units-wheel B⁵, date tens-wheel B⁶, and month-wheel B⁷, and also in this figure are shown the gear-wheels on the type-wheels heretofore referred to. 115

As in the case of the minute units-wheel before referred to, with the trains of gearing thus described, so the minute tens-wheel and hour-wheel would, if left to themselves, rotate continuously and at no specified moment 120 could they be relied upon to present indices at the proper printing-point, and in order to restrain them, while permitting power from the clock-train to be stored in their respective equalizing-springs, I preferably employ 125 locking wheels and levers quite similar to those described in my prior application, Serial No. 381,888, filed February 18, 1891, and consisting (see Figs. 6 and 7) particularly of locking-wheels b² b³, respectively, having 130 square notches between the teeth, into which fit correspondingly-shaped ends of the locking-levers b⁴ b⁵, which are held in engagement by the springs b⁶, but are adapted to be re-

leased by cams or projections on the preceding wheel—that is to say, the locking-lever b^4 for the minute tens-wheel is adapted to be released by the minute units-wheel and the locking-lever for the hour-wheel is adapted to be released by the minute tens-wheel. This is accomplished by locating cams b^6 on the minute units-wheel in position to lift the locking-lever b^4 by coöperation with the pins b^7 thereon at the moment when the minute units-wheel is passing from "9" to "0." In the illustration shown two sets of digits are shown on the minute units-wheel, and consequently two cams b^6 , dotted lines, Figs. 7 and 15, are necessary in order that the proper registration of the minutes may take place. On the minute tens-wheel, Fig. 14, are located similar cams b^8 , which engage similar pins b^9 on the locking-lever b^3 for the hour-wheel and release the same at the moment when the minute tens-wheel is passing from "5" to "0." it being necessary in the case of the minute tens-wheel to employ numerals running only from "0" to "5," as there are only indicated fifty odd minutes. On this wheel I have shown three sets of numerals, and it must therefore carry three cams b^8 .

In operating the month and date units and tens wheels it is not found expedient to drive them through the medium of springs, as before described, as their movement is very slow and has to be controlled in a somewhat peculiar manner, and hence I make use of the mechanism which, in my before-mentioned application, I have termed "operating-segments" and "mutilated gears" for rewinding the same. The operating-segments are plates or segments lettered in the present drawings E, which are journaled on the hubs of each of the three type-wheels last mentioned, being held thereon by collars e, Fig. 11, which permit of free and independent rotation. The same collars hold the locking-wheels E' in place, but the latter are connected rigidly with the wheels, being for this purpose preferably located inside or between the segments and wheels within the recess, as shown in Figs. 11 and 16. Each of the segments E, while they are free to rotate independently in one direction, is caused to lock with the type-wheel when moving in the opposite direction and rotate said type-wheel. This locking, or, more properly, ratchet, mechanism consists of a pivoted pawl f, which passes through an aperture e' in the segment and engages the locking-wheel, as shown in Figs. 12 and 16, the pawl being held in engagement by the spring f', Fig. 12, secured to the segment.

60 Besides the segment the date units-wheel carries a gear-wheel G, Fig. 8, which meshes with a gear-wheel G' on the shaft g, which shaft carries a corresponding pinion g', Fig. 9, meshing with the gear G², with which the mutilated gears g², Fig. 9, g³, Fig. 10, respectively, for the month and date tens-wheel are rigidly connected. Said mutilated gears are for

rewinding the segments for these last-mentioned wheels. They are, through the connections just described, turned in unison with the date units-wheel, and to cause the proper rewinding of the segment for the date units-wheel a connection with the clock-train is made as follows: On the shaft^{2d}, with which the mainspring-drums are connected, I provide at an internal point the pinion H, adjustably mounted thereon and meshing with a gear-wheel H', Fig. 8, which is mounted on the hub of the mutilated gear h for rewinding the segment of the date units-wheel. It will be understood, of course, that the relative proportion of the gears and the location of the teeth on the mutilated gears is such as that they are out of the way of the teeth on the segments at all times when said segments are to be moved, which being a matter for calculation is easily determined by those skilled in the art, as indicated in my before-mentioned application.

Each of the segments has a section of gear-teeth I at one side thereof, which mesh with pinions I', connected by flexible connections i with operating-springs I², Figs. 8, 9, 10, and 5, which are put under tension when the segments are moved by the mutilated gears, and in order to prevent said segments escaping from said pinions I' or making too great a movement, which might occur under some circumstances, the section of gearing I terminates in a wide tooth I³ or projection, which cannot pass the pinions, and hence when this portion reaches said pinion the segment is of necessity arrested in this foreward movement.

Thus far in connection with the month and date wheels I have provided mechanism only for causing their forward movement which, if unrestrained, would prevent any proper registration or coöperation of the parts. To accomplish a proper registration, they are held in check against the tension of the operating-springs I² by means of locking-levers K K' K² for the date units, date tens, and month wheels, respectively, Figs. 8, 9, and 10, which locking-levers are similar to those heretofore described and engage the locking-wheels E' in similar manner. The locking-lever K for the date units-wheel is adapted to be released once in twenty-four hours by means of the hour-wheel, which latter, therefore, is provided with one cam k and with a series of indices representing the hours for the complete day—a. m. and p. m. The single cam k under ordinary circumstances coöperates with the pin k' on the locking-lever K and releases the same to turn the units-wheel forward one space once in twenty-four hours, and the units-wheel is caused to release the tens-wheel not directly, as in the former instance, but through the medium of the mutilated gear for rewinding the segment of the tens-wheel, which mutilated gear, as before mentioned, moves in unison with the units-wheel. This gear carries, preferably, on a disk secured on one side thereof pairs of projec-

tions or cams l , Fig. 20, which pass beneath and elevate a releasing-lever L , connected rigidly with the locking-lever K' . Thus when said cams or projections are brought to the proper point they release said locking-lever and permit the tens-wheel to advance. The month-wheel locking-lever is operated in a similar manner by means of a single projection l' on the mutilated gear g^3 , Fig. 10, which passes beneath a lever L' on the locking-lever K^2 .

As accessory to the skipping mechanism for the long and short months to be now described the date units-wheel is provided with two sets of digits and two extra figures "1." Thus the indices read "0," "1," "1," "2," "3," &c., to "9," when the same order is repeated, and the date tens-wheel is provided with three sets of numerals, consisting of two figures "1," two figures "2," and a single figure "3," with a space equal to the single figure between each set of figures. Thus on this wheel the appearance is first a space or blank, then two figures "1," followed by two figures "2," a single figure "3," another blank, &c., Fig. 25.

Besides being released by the cam on the hour-wheel the locking-lever K is adapted to be released at certain intervals to compensate for the skipping of the dates at the end of short months and also to skip the extra one on the date units-wheel at the tenth and twentieth day, which is accomplished by mounting on the side of the mutilated gear g^3 , opposite to the cam l , three series of projections adapted to coöperate with the skipping-lever M , which engages a pin M' on the locking-lever K for the date units-wheel, Figs. 8 and 9. One of these projections m , which is adapted to compensate for the skipping of days at the ends of the months, is in the form of three steps, Fig. 23, any one of which is engaged by the lever M , according to the longitudinal position of the shaft carrying said lever, as will be presently explained, and the remaining two projections m' cause the proper skipping at the tenth and twentieth days. The operation of this particular mechanism is as follows: Assuming that the date units-wheel is indicating the first part of the month, from the first to the ninth day, at the moment it moves from "9" to "0" the first of the pairs of projections l , Figs. 9 and 20, coöperates with the lever L and permits the tens-wheel to advance from the blank space to "1," causing the next impression to be for the tenth day. As the units-wheel continues to rotate the second figure "1" thereon is brought to the printing-point by reason of the engagement of one of the projections m' with the skipping-lever M , causing the locking-lever K to be disengaged during the passage of a second tooth, the pin k' engaging the cam k on the hour-wheel, causing the release for the passage of the first tooth, the result being, as just stated, the second figure "1" is brought to the printing-point and with

the first figure "1" on the tens-wheel makes the impression for the eleventh day. The second of the pair of projections l now comes into action as the units-wheel moves from the second figure "1" to the figure "2" and causes the tens-wheel to have another movement—namely, from the first to the second figure "1." Thus the next imprint will be proper for the twelfth day. The units-wheel then continues its regular motion until the end of the nineteenth day, when as it moves from the "9" to "0" the first figure "2" on the tens-wheel will be advanced to the printing position by reason of the engagement of the first one of the next pair of projections or cams l causing imprint of the twentieth day to be made. The units-wheel then advances two spaces, skipping the first and bringing the second figure "1" into the printing position, indicating the twenty-first day, the action being the same as described with relation to the twelfth day—namely, one of the pins m' passes beneath the lever M , elevates the locking-lever K , and brings the second figure "1" to the printing-point on the units-wheel—and as the units-wheel moves from "1" to "2" the second one of the pair of projections l causes the tens-wheel to advance, bringing the second figure "2" into position to indicate the twenty-second day. This order is then maintained until the end of the month is reached, when a variable skipping has to be made and in which use is made of the projection m , having three steps thereon, as before described, as follows:

The lever M is mounted on the shaft M' , which is longitudinally movable in its bearings and provided with a spring M^3 , Fig. 18, to hold the lever in position and the knurl M' for drawing it in the opposite direction, with an irregular cam M^3 for holding the shaft and lever in proper longitudinal position according to the number of days to be skipped. Thus when the month has but twenty-eight days the shaft is moved to throw the pin M' on the highest cam, which throws the lever M into position for engaging the first step on the projection m . This occurs as the units-wheel is passing from "8" to "9" and causes the locking-lever K to be held out of engagement until the second figure "1" is brought to the printing-point, the tens-wheel in the meanwhile having made two skips by reason of the passage of both of the projections l beneath the lever L . Therefore it presents a blank, and the next indication will be for the first day of the month. Should the month have thirty-one days, the lever M and its shaft are moved to a position beyond any of the steps, and therefore the units-wheel is advanced regularly step by step, the first figure "1" indicating the thirty-first day and the second figure "1" the first day of the next month, the tens-wheel being advanced as before explained. The month-wheel is automatically advanced under all circumstances as the date tens-wheel moves from figure "3" to blank,

but as the mutilated gear for rewinding the month-wheel segment upon which the projection l' for releasing the month-wheel-locking lever is located makes but one revolution in a month by reason of the gearing G' , g , g' , and G^2 , before explained, the release of the locking-lever K^2 is easily regulated. With this arrangement it is necessary only to set the pointer m^5 , Fig. 4, at any time during the month to point to the space indicated on the dial as proper for the number of days contained in that month. Thus if a month have twenty-nine days the pointer is turned to the number "29" on the dial, which places the pin M^6 on the second highest cam, and for months containing the other numbers of days it is correspondingly adjusted, always causing the skipping-lever to move to the proper position for skipping the requisite number of days.

By arranging the gearing, skipping, and releasing mechanism for the month and date wheels as thus described I am enabled to employ but few and inexpensive parts, the printing-wheels are brought close together, making a proper indication, and the accuracy of the operation is insured, besides which a most important result may be accomplished—namely, that of the setting of the date-wheels without the necessity of going through the extremely tedious operation of setting the stamp by turning the minute-wheel or by taking the mechanism apart. This result, which is of very great importance, is accomplished by mounting the mutilated gears g^3 , g^3 and the attached gear-wheel G^2 rigidly on a shaft O , which extends out in rear of the frame and is provided with a knurl O' for turning said mutilated gear and through the gear G^2 , pinion g' , and gear G' turning the date units-wheel, the locking-wheel for the latter of course having been released preferably by means of the handle o , attached to the shaft o' , on which the locking-lever K is rigidly mounted, said handle o being in convenient position for operation simultaneously with the turning of the knurl O' .

With this setting mechanism for the date and month wheels, in connection with the setting mechanism before described for the minute and hour wheels, the stamp may be quickly and accurately set, a convenience which will be at once appreciated by those handling this class of stamps as heretofore constructed.

If reference be made to Fig. 23, the proper relative relation of the stepped projection m , cams or projections l , and projections l' will be seen, and it will be noted that the last projection l of the pair and the projection l' operate at nearly the same moment with the last step on the cam m .

The main operating-springs are manually wound by a key applied to the stems A^6 in the usual manner, and to the back end of the shaft 2^d a suitable hour-hand for indicating the hour on a dial P at the front of the clock

is provided, and on the shaft 4^d is secured a gear-wheel p , which meshes with a pinion mounted on a sleeve p' , carrying a minute-hand for indicating the minutes on said dial, the sleeve itself being journaled on a projecting end of shaft 2^d , as shown clearly in Fig. 3.

The year-wheel is adapted to be moved by hand at the end of the year, and for the purpose of holding it in place it is provided with a series of depressions or openings Q , into which a spring retaining-finger Q' fits, as will be readily understood, this feature being common to stamps heretofore constructed.

The casing in which the mechanism is mounted is preferably rectangular and provided with means for securely closing against meddlesome persons, the only parts exposed being the peripheries of the type-wheels at the printing-point, and as these are locked against movement in both directions practically there is little or no danger of the stamp being intentionally altered as to the date indicated.

The platen or pad R for driving the paper or material upon which the impression is made against the type-wheel is mounted on an overhanging arm R' , which is securely fastened to the door R^2 , forming the rear side of the machine, and is journaled on vertical pivots, as shown in Fig. 2, which construction, besides forming a very neat and easily-constructed one, absolutely prevents injury to the stamp by striking the type-wheel with the platen during the time the door is open and the type-wheels are being set, as when said door is open the platen is of necessity thrown off to one side.

The stamp as a whole has been found exceedingly efficient in practice, and by reason of the particular manner of equalizing the load on the mainspring of the motor practically no variation in the clock-train is caused by the irregular movement of the type-wheel, and, further, by arranging the bearings for the escapement-wheel and pallet in a vertical plane, or in a plane parallel with the direction of the impact or shock given in making an impression, little or no inconvenience results when an impression is made at the moment the pallet is in engagement with the escapement-wheel.

Having thus described my invention, what I claim as new is—

1. In a time-stamp, the combination with the clock-train and the minute and hour wheels gearing on said train through intermediate equalizing-springs, of the date and month wheels having independent actuating-springs rewound by the clock-train at stated intervals, substantially as described.

2. In a time-stamp, the combination with the clock-train, hour and minute wheels gearing therewith through intermediate equalizing-springs, of the month and date wheels, the operating spring-operated segments therefore, and the mutilated gears driven from the clock-train for rewinding said segments, substantially as described.

3. In a time-stamp, the combination with the constantly-moving clock-train, the date units-wheel, its spring-operated actuating-segment, the mutilated gear for rewinding said segment in train with the clock-train, of the date tens-wheel and month-wheel, their spring-operated actuating-segments, the mutilated gears for rewinding said segments in train with the units-wheel of the locking-levers for said wheels and the pins on the said last-mentioned mutilated gears for releasing said levers, substantially as described.

4. In a time-stamp, the combination with the constantly-moving clock-train, the date units-wheel, its spring-operated actuating-segment and the mutilated gear in train with the clock-train for rewinding said segment, of the date tens-wheel and month-wheel, their spring-operated actuating-segments, the mutilated gears in train with the units-wheel for rewinding said segments, the locking-lever for the units-wheel and the stop-cam for holding said lever out of engagement at the end of the short months, moving in unison with the mutilated gear for rewinding the tens-wheel, substantially as described.

5. In a time-stamp, the combination with the date units-wheel, the spring-operated actuating-segment therefor, the clock-train and the mutilated gear-train driven by the said clock-train, and the gear in train with said units-wheel of the locking-lever for said units-wheel and the skipping projection moved by said gear-wheel for holding the locking-lever out of engagement at the ends of the short months, substantially as described.

6. In a time-stamp, the combination with the constantly-moving clock-train, the date units-wheel driven therefrom, of the date tens-wheel, the month-wheel, their actuating-segments and the mutilated gears for rewinding said segments in train with the units-wheel, of the locking-levers for the tens and month wheels and the releasing projections on the mutilated gears for releasing said levers, substantially as described.

7. In a time-stamp, the combination with the constantly-moving clock-train, the hour-wheel driven therefrom, the date units-wheel, its locking-lever and the cam on the hour-wheel for releasing said lever, of the date tens and month wheels their locking-levers and the wheels driven by the date units-wheel carrying releasing projections co-operating with said last-mentioned locking-levers to release the date tens and month wheels respectively at the proper moment with relation to the units-wheel, substantially as described.

8. In a time-stamp, the combination with the date and month wheels, the spring-operated actuating-segment for the date-wheel, the clock-train and the mutilated gear driven by the clock-train for rewinding said segment at predetermined intervals, the actuating-seg-

ment for the month-wheel, the mutilated gear for rewinding said segment at predetermined intervals, in train with the date-wheel and the shaft on which said last-mentioned mutilated gear is mounted having the extended end and knurl by which said wheels may be set, substantially as described.

9. In a time-stamp, the combination with the constantly-moving clock-train, the date units-wheel, its actuating-segment connected therewith by a ratchet connection, the mutilated gear driven by the clock-train for rewinding said segment and the locking-levers for the wheel of the date tens-wheel and month-wheel, the gearing for rewinding their actuating mechanism in train with the units-wheel, the extended shaft on which said gearing is mounted, the knurl on said shaft and the handle for releasing the locking-lever of the units-wheel, whereby said parts may be set to the proper date, substantially as described.

10. In a time-stamp, the combination with the constantly-acting clock-train the date units-wheel, its spring-operated actuating-segment, the mutilated gear for rewinding said segment driven by the clock-train and the locking-lever for said wheel, of the date tens and month wheels, their actuating-segments, the mutilated gears for rewinding said segments mounted on a shaft, the knurl on the end of said shaft, the gearing connecting said mutilated gears and date units-wheel and the handle for releasing the locking-lever of said last-mentioned wheel, substantially as described.

11. In a time-stamp, the combination with the motor-train and date-wheel actuated therefrom, the locking-lever for said date-wheel-moving cam for releasing said locking-lever and the laterally-movable arm or skipping-lever forming the connection between said cam and lever, the knurl for setting said arm at the proper position to skip days at the end of the short months, and the intermediate shaft, substantially as described.

12. In a time-stamp, the combination with the motor-train, the date-wheel, its locking-lever and the wheel carrying the cam driven by said date-wheel, the laterally-movable arm or skipping-lever, adapted to engage said cam and locking-lever, the handle and the rest for holding said arm in position to skip the proper number of days at the ends of the short months, substantially as described.

13. In a time-stamp, the combination with the motor-train, the date units-wheel, its actuating-segment rewound from said motor-train, its locking-lever and the skipping-lever mounted on a shaft to move transversely, of the date tens-wheel and month-wheel their actuating-segments, and the mutilated gears driven from the units-wheel for rewinding said segments, the cam on one of said mutilated gears adapted to contact with the skipping-lever when moved transversely to the

proper points for releasing the locking-levers to skip days at the ends of the short months, substantially as described.

14. The combination with the motor-train, 5 the date units-wheel, its actuating-segment rewound from the motor-train, the set of indices on the said units-wheel having two figures "1," and the locking-lever for said wheel, of the skipping-lever for releasing said locking-lever, the wheel in gear with the units-wheel and the projections or pins on said wheel coöperating with the skipping-lever to hold the locking-lever out of engagement until the extra "1" is skipped at the tenth and 15 twentieth days practically, substantially as described.

15. In a time-stamp, the combination with the date units and date tens wheels, bearing sets of indices having two figures "1" at the 20 beginning of each set, the actuating-segments for said type-wheels, the motor-train, the mutilated gear for rewinding the segment of the units-wheel driven from the motor-train, the mutilated gear for rewinding the segment of 25 the tens-wheel driven from the units-wheel, the locking-levers for said wheels and their releasing-levers, of the projections of said last-mentioned mutilated gear engaging the releasing-levers at the tenth and twentieth 30 days to skip the extra figure "1" on the units-wheel and advance the second figure "1" on the tens-wheel to the printing-point, substantially as described.

16. In a time-stamp, the combination with 35 the motor-train, date units and date tens wheels, their actuating-segments, the mutilated gear driven by the motor-train for rewinding the segment of the units-wheel, the mutilated gear for rewinding the segment of 40 the tens-wheel driven by the units-wheel, the locking-levers for said wheels and their releasing-levers, of the single projection at the tenth and twentieth day for holding the locking-lever for the units-wheel out of engagement and the double cam for releasing the locking-lever for the tens-wheel, said cams or projections moving in unison with the 45 units-wheel; substantially as described.

17. In a time-stamp, the combination with 50 the date units and date tens wheels, the sets of indices on the units-wheel, having two figures "1," the sets of indices on the tens-wheel having two figures "1," two figures "2," a single figure "3," and a space between said 55 sets, the actuating-segments for said wheels the locking-levers for holding the wheels in check, the wheels driven from the units-wheel carrying the projections for holding the units-wheel-locking lever out of engagement at the 60 tenth and twentieth days and the step-cam for varying the extent of its release at the end of the short months and the double-pointed cam for releasing the locking-lever for the tens-wheel to advance the said tens-wheel twice in succession at the tenth and 65 twentieth days and at the end of the months; respectively, substantially as described.

18. In a time-stamp, the combination with the type-wheels, clock-train, locking-levers, skipping-lever for the date-wheel, step-cam 70 in the type-wheel train and complemental parts, substantially as described, of the movable shaft carrying the skipping-lever, the step-cam for holding said shaft and lever in proper position to engage any one of the steps 75 of the cam in the type-wheel train, and the handle and spring for moving said shaft to the required position, substantially as described.

19. In a time-stamp, the combination with the constantly-moving motor-train, the type-wheel driven thereby and the stop-wheel controlling said type-wheel released by the motor-train and a clutch interposed between the stop-wheel-releasing mechanism and escapement end of the motor-train, and a handle 80 or knurl controlling said clutch whereby the stop-wheel may be released from the escapement end of the motor-train, and the type-wheel set, substantially as described.

20. In a time-stamp, the combination with 90 the clock-train, the minute type-wheel driven therefrom through an intermediate spring, the stop-wheel controlling the minute type-wheel and the stop moved by the clock-train for releasing said stop-wheel at predetermined 95 intervals, of a clutch interposed between the said stop and escapement mechanism of the clock-train and a handle in gear with the stop for moving the same in advance of the movement of the escapement mechanism of 100 the clock-train, whereby the minute-wheel may be set, substantially as described.

21. In a time-stamp, the combination with the clock-train, the minute-wheel driven therefrom through an intermediate spring, 105 the stop-wheel in gear with the minute-wheel, the stop for releasing the said stop-wheel, the gear controlling said stop and the clutch connection between said gear and escapement end of the clock-train and the handle 110 controlling said stop, whereby the same may be moved in advance of the escapement end of the clock-train to set the minute-wheel, substantially as described.

22. In a time-stamp, the combination with 115 the clock-train, the minute-wheel driven therefrom through an intermediate spring, the stop-wheel in gear with said minute-wheel and the stop for said wheel the gear-wheel meshing with the escapement end of the 120 clock-train the gear-wheel moving the stop and the clutch connection between said last-mentioned gear-wheels and the handle controlling the movement of the stop-moving wheel in advance of the escapement end of 125 the clock-train, substantially as described.

23. In a time-stamp, the combination with the clock-train, the minute-wheel driven therefrom through an intermediate spring, 130 the stop-wheel in gear with the minute-wheel, the stop for said wheel and the gear-wheel controlling said stop having a handle for moving the same, of the gear-wheel mounted on the shaft with the stop-moving gear and mesh-

ing with the clock-train, a clutch connection between said gear-wheels and the spring for moving said wheels into engagement whereby the minute-wheel may be set in advance of the clock-train, substantially as described. 5

24. In a time-stamp, the combination with the motor-train type-wheels and complementary parts, of the spring-pressed actuating-segments for the type-wheels journaled on the 10 hubs of said wheels and set by the motor-train; substantially as described.

25. In a time-stamp, the combination with the motor-train, complementary parts and type-wheels having the extended hubs, of the 15 lock-wheels rigidly affixed on said hubs, the actuating-segments journaled on said hubs and meshing with the motor-train and the retaining-collars for said segments; substantially as described. 20

26. In a time-stamp, the combination with the spring-impelled type-wheel, the locking- 25

wheel thereon and the locking-lever engaging the latter to hold the type-wheel against movement in either direction, of the spring-impelled minute type-wheel controlling said locking-lever whereby it is released and the wheel permitted to rotate under the influence of its impelling-spring, the constantly-acting motor-train and the stop for the minute-wheel released thereby at stated intervals; 30 substantially as described.

27. In a time-stamp, the combination with the spring-impelled type-wheels carrying locking-wheels and the locking-levers engaging said wheels to prevent their rotation, of 35 the motor-train and the intermittently-operated wheels driven therefrom, for releasing the locking-lever; substantially as described.

CHARLES STAHLBERG.
